FLOW CONTROLLING DEVICE FOR
REFRIGERATING SYSTEMSDelbert F. Newman, Schenectady, N. Y., assignor
to General Electric Company, a corporation of
New York

Application January 18, 1936, Serial No. 59,739

6 Claims. (Cl. 138—42)

My invention relates to flow controlling devices for controlling the flow of refrigerant between the high and low pressure sides of refrigerating systems.

5 It has heretofore been proposed to utilize long capillary tubes having a comparatively small inside diameter to maintain the required difference in pressure between the high and low pressure sides of a refrigerating system. Such a device 10 must be arranged to restrict the flow of vaporized refrigerant from the high pressure side of the system to the low pressure side thereof, while at the same time permitting the flow of sufficient liquid refrigerant therethrough to meet the capacity requirements of the system at the lowest pressure difference prevailing between the high and low pressure sides of the system during the normal operation thereof. Although such capillary tubes are simpler and more economical to 15 construct than the float valves or other devices having moving parts, which have heretofore been used as flow controlling devices between the high and low pressure sides of refrigerating systems, such capillary tubes are nevertheless bulky and 20 susceptible to damage since such a tube may be easily crushed thus shutting off the flow of refrigerant therethrough and rendering the refrigerating system inoperative.

It is an object of my invention to provide a flow 25 controlling device for controlling the flow of refrigerant between the high and low pressure sides of a refrigerating system which comprises an improved arrangement of sheet metal parts that are economical to manufacture, the flow controlling 30 device being effective in operation and rugged in construction.

Further objects and advantages of my invention will become apparent as the following description proceeds and the features of novelty 35 which characterize my invention will be pointed out with particularity in the claims annexed to and forming a part of this specification.

For a better understanding of my invention, reference may be had to the accompanying drawings in which Fig. 1 is a side elevation, partly in section, of a refrigerating machine provided with a flow controlling device embodying my invention; Fig. 2 is a perspective view of the flow controlling device of the refrigerating machine shown in Fig. 1; Fig. 3 is a developed view of the flow controlling device shown in Figs. 1 and 2, portions of the flow controlling device being broken away in order to better illustrate the internal construction thereof; Fig. 4 is a sectional view along the line 4—4 of the flow controlling device shown in Fig. 3;

Fig. 5 is a developed view of a modified form of flow controlling device, embodying my invention, which may be used in the refrigerating machine shown in Fig. 1, and Fig. 6 is a sectional view along the line 6—6 of the flow controlling device shown in Fig. 5.

Referring to the drawing, I have shown in Fig. 1 a refrigerating machine, designed for household use, which includes a motor driven compressor unit contained in a cylindrical hermetically sealed 10 casing 10 mounted on the upper side of a removable heat insulated top wall 11 of the refrigerator cabinet in which the refrigerating machine is used. Compressed vaporized refrigerant, such as sulphur dioxide, is supplied from the compressor 15 contained in the casing 10 to a cylindrical sheet metal condenser 12 which surrounds the casing 10 and is mounted thereon. The compressed gaseous refrigerant thus supplied to the condenser 12 circulates through a helical refrigerant 20 circulatory passage 13 formed in the condenser 12 and is liquefied by the transfer of heat therefrom to the cooling air which circulates over the surfaces of the condenser. The cooling air circulates upwardly over the surfaces of the condenser 12 and between the condenser and the casing 10 by natural draft. The refrigerant thus liquefied in the condenser 12 flows through a conduit 14 to a cylindrical receiver 15 which is mounted on the wall 11. Liquid refrigerant accumulated in the receiver 15 flows therefrom through a conduit 16 to a flow controlling device 17 embodying my invention and is supplied therefrom through a liquid line 18 to a flooded type sheet metal evaporator 19.

The evaporator 19 is supported on the lower side of the wall 11 in a refrigerator cabinet food storage compartment, the contents of which is to be cooled. The evaporator 19 is provided with a plurality of refrigerant circulatory passages 20 40 which communicate with a longitudinal cylindrical header 21 below the normal liquid level therein. The header 21 is maintained about half full of liquid refrigerant and the refrigerant circulatory passages 20 are thus flooded with liquid 45 refrigerant. The liquid refrigerant contained in the evaporator 19 is vaporized by the absorption of heat from the compartment in which the evaporator is located and the refrigerant thus vaporized is collected in the header 21 above the level 50 of the liquid refrigerant therein. The vaporized refrigerant thus collected in the header 21 is returned to the compressor in the casing 10 through a suction conduit 22 which communicates with the header 21 above the normal liquid level there- 55

in. This cycle is repeated and continued until the temperature of the compartment in which the evaporator 19 is located is reduced to the desired value.

5 The flow controlling device 17 includes an elongated substantially rectangular sheet of metal 23 and complementary rectangular sheets of metal 24 and 25, which are arranged on opposite sides of the sheet of metal 23 and conform thereto throughout their length. The sheets of metal 23, 24, and 25 are preferably made of cold-rolled steel. A relatively narrow elongated zigzag slot is formed in the sheet of metal 23. This elongated slot preferably includes a plurality of transverse slots 26 arranged in substantially parallel relation. These slots 26 are connected in series relation by a plurality of longitudinal slots 27 arranged at the alternate opposite ends thereof and extending between the adjacent end portions 10 of the transverse slots 26. It will be noted that the longitudinal slots 27 communicate with the transverse slots 26 intermediate the ends thereof, so that small recesses or pockets 28, arranged in alignment with the adjacent portions of the transverse slots 26, are formed at the opposite ends of the latter. Since the recesses 28 are located adjacent the reentrant bends formed in the zigzag or sinuous fluid passage composed of the slots 26 and 27, the recesses serve to increase 15 the turbulence of any vaporized refrigerant as it flows from the slots 26 to the slots 27 or from the slots 27 to the slots 26. Both the slots 26 and 27 are of relatively small cross section in order to 20 restrict or substantially prevent the flow of vapor therethrough. The slots 26 and 27 are preferably about .001 square inch in cross sectional area when the flow controlling device is used with a refrigerating machine having a capacity of about 25 550 B. t. u.'s per hour, using sulphur dioxide as a refrigerant, and operating in an ambient temperature of 100° F. The provision of a flow controlling device for controlling the flow of refrigerant between the high and low pressure sides of a refrigerating system and comprising a member 30 having a plurality of fluid passages formed therein and arranged in substantially parallel relation, and an arrangement including a plurality of connecting passages formed in said member for connecting the fluid passages in series relation, the 35 connecting passages being arranged at alternate opposite ends of the fluid passages and communicating with adjacent end portions thereof intermediate the ends of said fluid passages is not my 40 invention, but is the invention of Christian Steenstrup and is described in his copending application Serial No. 59,756, filed January 18, 1936, and assigned to the General Electric Company, the assignee of my present invention.

45 The sheet of metal 25 is preferably of the same peripheral dimensions as the sheet of metal 23, while the sheet of metal 24 is somewhat wider than the sheets 23 and 25. The longitudinal edges 29 and 30 of the sheet 24 are folded over 50 the adjacent longitudinal edges of the sheets 23 and 25 and the sheets are brazed or otherwise hermetically sealed together. Complementary semi-cylindrical indentations 31 and 32 are formed in the sheets of metal 24 and 25, respectively, at adjacent ends thereof. The indentations 31 and 32 are tightly fitted around the lower end of the conduit 16 and are brazed or otherwise hermetically sealed thereto. One of 55 70 75 the slots 26, located at an end of the series of

such slots, communicates with the complementary indentations 31 and 32. A similar pair of complementary semi-cylindrical indentations 33 and 34 are formed in the sheets of metal 24 and 25, respectively, and communicate with the one of the slots 26 located at the opposite end of the series of such slots. These indentations 33 and 34 are tightly fitted on the upper end of the liquid line 18 being brazed or otherwise hermetically sealed thereto and thus forming an outlet for the 10 flow controlling device 17.

In making the flow controlling device 17 described above, the slots 26 and 27 as well as the recesses or notches 28 are punched or otherwise formed in the sheet of metal 23. The complementary indentations 31, 32, 33, and 34 are stamped or otherwise formed in the flat sheets of metal 24 and 25. The sheets of metal 24 and 25 are then arranged in face contact with the sheet of metal 23 on opposite sides thereof and in such position that they conform with each other throughout substantially their entire lengths. The edges 29 and 30 of the sheet of metal 24 are then folded over the adjacent edges of the sheets of metal 23 and 25. The sheets of metal 23, 24, 25 and 26 are then brazed together throughout the area of the contacting surfaces thereof or are otherwise hermetically secured together. After having been thus secured together the sheets of metal 23, 24, and 25 are then wound into a helical 30 form, their finished shape being illustrated in Fig. 2. Thermal insulation 35 is arranged between adjacent layers of the helically wound sheets of metal in order to prevent the transfer of heat between bodies of refrigerant passing through the fluid passage made up of the slots 26 and 27 in the adjacent portions of the flow controlling device. The flow controlling device 17 thus formed is preferably mounted in the heat insulation 11a of the refrigerator cabinet wall 11.

It will thus be seen that the slots 26, 27, and 40 45 50 55 60 65 70 75 80 85 90 95 98 99 100 101 102 103 104 105 106 107 108 109 110 111 112 113 114 115 116 117 118 119 120 121 122 123 124 125 126 127 128 129 130 131 132 133 134 135 136 137 138 139 140 141 142 143 144 145 146 147 148 149 150 151 152 153 154 155 156 157 158 159 159 160 161 162 163 164 165 166 167 168 169 170 171 172 173 174 175 176 177 178 179 180 181 182 183 184 185 186 187 188 189 190 191 192 193 194 195 196 197 198 199 200 201 202 203 204 205 206 207 208 209 210 211 212 213 214 215 216 217 218 219 220 221 222 223 224 225 226 227 228 229 230 231 232 233 234 235 236 237 238 239 239 240 241 242 243 244 245 246 247 248 249 249 250 251 252 253 254 255 256 257 258 259 259 260 261 262 263 264 265 266 267 268 269 269 270 271 272 273 274 275 276 277 278 279 279 280 281 282 283 284 285 286 287 288 289 289 290 291 292 293 294 295 296 297 298 299 299 300 301 302 303 304 305 306 307 308 309 309 310 311 312 313 314 315 316 317 318 319 319 320 321 322 323 324 325 326 327 328 329 329 330 331 332 333 334 335 336 337 338 339 339 340 341 342 343 344 345 346 347 348 349 349 350 351 352 353 354 355 356 357 358 359 359 360 361 362 363 364 365 366 367 368 369 369 370 371 372 373 374 375 376 377 378 379 379 380 381 382 383 384 385 386 387 388 389 389 390 391 392 393 394 395 396 397 398 398 399 399 400 401 402 403 404 405 406 407 408 409 409 410 411 412 413 414 415 416 417 418 419 419 420 421 422 423 424 425 426 427 428 429 429 430 431 432 433 434 435 436 437 438 439 439 440 441 442 443 444 445 446 447 448 449 449 450 451 452 453 454 455 456 457 458 459 459 460 461 462 463 464 465 466 467 468 469 469 470 471 472 473 474 475 476 477 478 479 479 480 481 482 483 484 485 486 487 488 489 489 490 491 492 493 494 495 496 497 498 498 499 499 500 501 502 503 504 505 506 507 508 509 509 510 511 512 513 514 515 516 517 518 519 519 520 521 522 523 524 525 526 527 528 529 529 530 531 532 533 534 535 536 537 538 539 539 540 541 542 543 544 545 546 547 548 549 549 550 551 552 553 554 555 556 557 558 559 559 560 561 562 563 564 565 566 567 568 569 569 570 571 572 573 574 575 576 577 578 579 579 580 581 582 583 584 585 586 587 588 589 589 590 591 592 593 594 595 596 597 597 598 599 599 600 601 602 603 604 605 606 607 608 609 609 610 611 612 613 614 615 616 617 618 619 619 620 621 622 623 624 625 626 627 628 629 629 630 631 632 633 634 635 636 637 638 639 639 640 641 642 643 644 645 646 647 648 649 649 650 651 652 653 654 655 656 657 658 659 659 660 661 662 663 664 665 666 667 668 669 669 670 671 672 673 674 675 676 677 678 679 679 680 681 682 683 684 685 686 687 688 689 689 690 691 692 693 694 695 696 697 697 698 699 699 700 701 702 703 704 705 706 707 708 709 709 710 711 712 713 714 715 716 717 718 719 719 720 721 722 723 724 725 726 727 728 729 729 730 731 732 733 734 735 736 737 738 739 739 740 741 742 743 744 745 746 747 748 749 749 750 751 752 753 754 755 756 757 758 759 759 760 761 762 763 764 765 766 767 768 769 769 770 771 772 773 774 775 776 777 778 779 779 780 781 782 783 784 785 786 787 788 789 789 790 791 792 793 794 795 796 797 797 798 799 799 800 801 802 803 804 805 806 807 808 809 809 810 811 812 813 814 815 816 817 818 819 819 820 821 822 823 824 825 826 827 828 829 829 830 831 832 833 834 835 836 837 838 839 839 840 841 842 843 844 845 846 847 848 849 849 850 851 852 853 854 855 856 857 858 859 859 860 861 862 863 864 865 866 867 868 869 869 870 871 872 873 874 875 876 877 878 879 879 880 881 882 883 884 885 886 887 888 889 889 890 891 892 893 894 895 896 897 897 898 899 899 900 901 902 903 904 905 906 907 908 909 909 910 911 912 913 914 915 916 917 917 918 919 919 920 921 922 923 924 925 926 927 928 929 929 930 931 932 933 934 935 936 937 938 939 939 940 941 942 943 944 945 946 947 948 949 949 950 951 952 953 954 955 956 957 958 959 959 960 961 962 963 964 965 966 967 968 969 969 970 971 972 973 974 975 976 977 978 979 979 980 981 982 983 984 985 986 987 988 989 989 990 991 992 993 994 995 996 997 997 998 999 999 1000

direction of its flow is less than in the case of the vapor. The flow controlling device, which I have illustrated, is compact and rugged and may be readily manufactured from sheet metal by well known and economical manufacturing operations. It is particularly desirable to form the refrigerant passage in the flow controlling device by slots in a sheet of metal rather than by indentations in a sheet of metal, for example, because the shearing die ordinarily used in forming the slots is less subject to wear than a compression or stamping die. Moreover, indentations made in a sheet of metal are subject to variations in size because of differences in the granular structure or thickness of the metal. Hence, the slots are of more uniform size than would be indentations. When the slotted sheets of metal 23 are handled and especially when they are handled in large quantities during factory production thereof, they may become twisted or skewed, that is, the longitudinal edges of the slotted sheets 23 may be moved lengthwise relative to each other so that some of the slots 26 and 27 are narrowed and others are widened thus materially changing their resistance to the flow of fluids therethrough. In Figs. 5 and 6, I have shown a modified form of flow controlling device 17a, embodying my invention, which is very similar to the flow controlling device 17 described above but in which this difficulty is obviated.

The flow controlling device 17a includes an elongated substantially rectangular sheet of metal 23a and complementary rectangular sheets of metal 24a and 25a which are arranged on opposite sides of the sheet of metal 23a and conform thereto throughout their length. The sheets of metal 23a, 24a, and 25a are preferably made of cold-rolled steel. A series of relatively narrow elongated zigzag slots are formed in the sheet of metal 23a. These elongated slots preferably include a plurality of transverse slots 26a arranged in substantially parallel relation. Groups of these slots 26a are connected in series relation by a plurality of longitudinal slots 27a arranged at the alternate opposite ends thereof and extending between the adjacent end portions of the transverse slots 26a. It will be noted that the longitudinal slots 27a communicate with the transverse slots 26a intermediate the ends thereof so that small recesses or pockets 28a, arranged in alignment with the adjacent portions of the transverse slots 26a, are formed in the opposite ends of the latter. Since the recesses 28a are located adjacent the reentrant bends formed in the zigzag or sinuous fluid passages composed of the slots 26a and 27a, the recesses serve to increase the turbulence of any vaporized refrigerant as it flows from the slots 26a to the slots 27a or from the slots 27a to the slots 26a. Both the slots 26a and 27a are of relatively small cross section in order to restrict or substantially prevent the flow of vapor therethrough. The slots 26a and 27a are preferably about .001 sq. in. in cross sectional area when the flow controlling device is used with a refrigerating machine having a capacity of about 550 B. t. u.'s per hour, using sulphur dioxide as a refrigerant, and operating in an ambient temperature of 100° F. From an inspection of Fig. 5, it will be seen that the series of zigzag passages formed in the sheet of metal 23a by the slots 26a and 27a are separated by unslotted portions of metal 23b. In other words, the construction of the sheet 23a

75 is the same as that of sheet 23 shown in Fig. 3

and described above, except that some of the connecting slots 27 in the sheet 23 are omitted in the sheet 23a. Consequently, the sheet 23a is much more rigid than the sheet 23 and is not likely to be skewed or twisted during handling.

The sheet of metal 25a is preferably of the same peripheral dimensions as the sheet 23a, while the sheet 24a is somewhat wider than the sheets 23a and 25a. The longitudinal edges 29a and 30a of the sheet 24a are folded over the 10 adjacent longitudinal edges of the sheets 23a and 25a and the sheets are brazed or otherwise hermetically sealed together. The plurality of zigzag passages formed by the slots 26a and 27a are connected in series relation by a plurality of 15 indentations 24b formed in the sheet of metal 24a. These indentations 24b connect the adjacent end portions of the slots 26a intermediate their ends and extend across the unslotted portions 23b of the sheet of metal 23a.

Complementary semi-cylindrical indentations 31a and 32a are formed in the sheets of metal 24a and 25a, respectively, at the adjacent ends thereof. The indentations 31a and 32a are adapted to be fitted around the lower end of 20 the conduit 16 shown in Fig. 1 and may be brazed or otherwise hermetically sealed thereto. One of the slots 26a located at one end of the series of such slots communicates with the complementary indentations 31a and 32a. A similar 30 pair of complementary semi-cylindrical indentations (not shown) are formed in the sheets of metal 24a and 25a at the opposite ends thereof and communicate with the one of the slots 26a located at the opposite end of the series of such 35 slots. These latter semi-cylindrical indentations are adapted to be tightly fitted about the upper end of the conduit 18 and brazed thereto, thus forming an outlet for the flow controlling device 17a. After the sheets of metal 23a, 24a, and 25a have been secured together as described above they are preferably bent into a compact helix.

It will thus be seen that the flow controlling device 17a is formed of relatively rigid parts which may be easily handled during the manufacture thereof without danger of injuring the same. Also the slots 26a and 27a may be formed by a shearing die in the sheet of metal 23a and, as a consequence, will have relatively uniform 50 dimensions. Although the indentations 24b in the sheet of metal 24a form a part of the fluid passage through the flow controlling device 17a, they constitute only a very minor part of the total length thereof. The indentations 24b 55 formed in the sheet of metal 24a will not have such uniform dimensions as a slot, for example, because of the inherent limitations, referred to above, of the stamping apparatus ordinarily used in producing such indentations. This variation 60 in the dimensions of the indentations 24b will not, however, materially affect the flow characteristics of the fluid passage formed in the flow controlling device 17a since the total overall length of the indentations 24b is small as compared to the overall length of the slots 26a and 27a.

While I have shown two particular embodiments of my invention in connection with a compression type refrigerating machine, especially designed for household use, I do not desire my invention to be limited to the particular construction shown and described and I intend in the appended claims to cover all modifications within the spirit and scope of my invention.

What I claim as new and desire to secure by Letters Patent of the United States, is:

1. A flow controlling device for controlling the flow of refrigerant between the high and low pressure sides of a refrigerating system comprising a portion of sheet metal having an elongated relatively narrow slot formed therein, complementary portions of sheet metal, arranged on opposite sides of said slotted portion of sheet metal and conforming thereto substantially throughout their length, and means for hermetically securing all of said portions of sheet metal together, said second named portions of sheet metal closing the sides of said slot and cooperating therewith to form an elongated fluid passage. 5
2. A flow controlling device for controlling the flow of refrigerant between the high and low pressure sides of a refrigerating system comprising a portion of sheet metal having an elongated zigzag relatively narrow slot formed therein, complementary portions of sheet metal arranged on opposite sides of said slotted portion of sheet metal and conforming thereto substantially throughout their length, and means for hermetically securing all of said portions of sheet metal together, said second named portions of sheet metal closing the sides of said zigzag slot and cooperating therewith to form an elongated fluid passage. 10
3. A flow controlling device for controlling the flow of refrigerant between the high and low pressure sides of a refrigerating system comprising an elongated substantially rectangular sheet of metal having a relatively narrow zigzag slot formed therein, complementary substantially rectangular sheets of metal arranged on opposite sides of said slotted sheet of metal in face contact therewith and conforming thereto substantially throughout their length, the longitudinal edges of one of said last named sheets of metal being folded over the adjacent longitudinal edges of the other sheets of metal, and means for hermetically securing all of said sheets of metal together, said second named sheets of metal closing the sides of said slot and cooperating therewith to form an elongated fluid passage. 15
4. A flow controlling device for controlling the flow of refrigerant between the high and low pressure sides of a refrigerating system comprising an elongated substantially rectangular sheet of metal having a plurality of transverse slots formed therein and arranged in substantially parallel relation, said sheet of metal having longitudinal slots therein arranged at alternate opposite ends of said transverse slots and extending between adjacent end portions thereof, said longitudinal slots communicating with said transverse slots intermediate the ends thereof, complementary rectangular sheets of metal arranged on opposite sides of said slotted sheet of metal in face contact therewith and conforming thereto substantially throughout their length, and means for hermetically securing all of said sheets of metal together, said second named sheets of metal closing the sides of said slots and cooperating therewith to form an elongated fluid passage. 20
5. A flow controlling device for controlling the flow of refrigerant between the high and low pressure sides of a refrigerating system comprising a portion of sheet metal having a plurality of elongated relatively narrow slots formed therein, complementary portions of sheet metal arranged on opposite sides of said slotted portion of sheet metal and conforming thereto substantially throughout their length, means for hermetically securing all of said portions of sheet metal together, said second named portions of sheet metal closing the sides of said slots and cooperating therewith to form a plurality of elongated fluid passages, and means including a plurality of indentations formed in at least one of said second named portions of sheet metal and extending between adjacent portions of said slots for connecting said elongated fluid passages in series relation. 25
6. A flow controlling device for controlling the flow of refrigerant between the high and low pressure sides of a refrigerating system comprising a portion of sheet metal having a plurality of elongated zigzag relatively narrow slots formed therein, complementary portions of sheet metal arranged on opposite sides of said slotted portion of sheet metal and conforming thereto substantially throughout their length, means for hermetically securing all of said portions of sheet metal together, said second named portions of sheet metal closing the sides of said zigzag slots and cooperating therewith to form a plurality of elongated fluid passages, and means including a plurality of indentations formed in at least one of said second named portions of sheet metal and extending between adjacent portions of said slots for connecting said elongated fluid passages in series relation. 30

DELBERT F. NEWMAN.
